UNITED STATES PATENT OFFICE

WILLIAM LESLIE GUY, OF BIRMINGHAM, ENGLAND, ASSIGNOR OF ONE-HALF TO A. M.
A. C. LIMITED, OF BIRMINGHAM, ENGLAND, A BRITISH COMPANY

CARBURETOR

Application filed February 26, 1926, Serial No. 90,881, and in Great Britain March 5, 1925.

This invention relates to carburetors for use with internal combustion engines, of the kind in which the fuel is supplied by a nozzle situated in a venturi forming a primary air supply passage into which is admitted a controllable supply of air, and the mixture thus obtained is delivered into the main air passage of the carburetor, usually at the throat of a choke tube therein, or at a part adjustably restricted by a throttle valve.

A construction has previously been proposed in which controllable air was admitted into the primary air passage at a position adjacent the latter's entry into the main air passage and entirely remote from the fuel nozzle or restricted part containing it, and it served, therefore, merely to dilute the mixture delivered. The principal object of the present invention, however, is to secure more perfect atomization of the fuel as well as to provide for varying the mixture strength.

In another proposed construction, a fuel nozzle has been located in a concentrically arranged atomizer tube in the main air passage of the carburetor, and this tube was provided with apertures at the level of the top of the nozzle, and also at a position near its outlet end, both sets of apertures being controllable by means of a rotatable sleeve surrounding the atomizer tube.

According to this invention, the whole of the controllable air supplied to the primary air passage is adapted to be admitted laterally into the Venturi tube therein at a position immediately opposite the top edge of the fuel nozzle.

In the preferred method of carrying out the invention, which is illustrated in the accompanying vertical section, the carburetor has a horizontal main passageway 2 controlled by a main throttle valve 3, and the primary air passage 4 is vertically arranged in the lower wall of the main air passage.

Within this primary air passage is located a Venturi choke tube 5, the upper edge of which may, if preferred, project somewhat into the main air passage 2. The choke tube is preferably contained in the thickened portion of the carburetor body into the under face of which is screwed the fuel nozzle 6 and

any suitable method of connecting the latter with a constant level float chamber (not shown) is adopted.

A comparatively small annular space is provided between the side of the fuel nozzle and the wall of the Venturi tube 5, and this forms a restricted passage for the supply of a certain amount of primary air which enters at 7, and, under normal conditions, requires no adjustment. Obviously, however, to suit certain engines, and/or certain kinds of fuel, the quantity of air thus admitted would be determined initially by experiment and the air passage at the mouth of the venturi arranged accordingly.

Lateral apertures or passages are provided in the side of the venturi 5, for example, one or more holes such as 8, and the lower edges of these passages (i. e., those nearest to the inlet of the venturi) are level or substantially so with the outlet of the fuel nozzle 6. Air reaches the hole or holes 8 through a passage 9 and annular chamber 10, and the inlet 12 to this passage is controlled by any suitable kind of valve, such, for example, as a spring-loaded plug valve 11 which normally closes the inlet to it but is adjustable by cable or other mechanism.

By the foregoing arrangement, it is possible to control very effectively the mixture strength merely by adjustment of the air supply to the aperture 8 or apertures in the venturi 5, and there is no necessity whatever to provide in the main passageway 2, an unduly small choke tube, into the throat of which the primary mixture passage would deliver.

A specially important feature, however, is the thorough atomization of the fuel which can be obtained owing to the particular location of the air inlet 8 in the Venturi tube with respect to the outlet of the nozzle 6.

The invention can be applied either to a single nozzle carburetor (or to a two nozzle carburetor) i. e., one in which a pilot nozzle is fitted. In the latter case it would be applied to the main nozzle.

What I claim as my invention and desire to secure by Letters Patent of the United States is:

1. In a carburetor having a main passage-

- way, a choke tube in communication with said main passageway, a primary air inlet passageway communicating with said choke tube, a fuel nozzle within said choke tube forming an annular restricted primary air passageway therebetween, a single laterally disposed aperture through the side of said choke tube having its lower edge substantially level with the outlet of the fuel nozzle, and forming the sole opening through the wall of said choke tube between the outlet of the nozzle and the mouth of the choke tube, and means for controlling the admission of air through said aperture.
2. In a carburetor for an internal combustion engine, the combination of a main passageway, a slideable throttle valve controlling said passageway, a choke tube opening into said main passageway so that flow through this passageway takes place across its outlet, a fuel nozzle within said choke tube between which latter and the nozzle is an annular space forming a restricted passage for the supply of primary air, a lateral aperture in the side of said choke tube having its lower edge substantially level with the outlet of the fuel nozzle, a passage connecting said aperture with the atmosphere, a plug valve adapted normally to close the inlet to said latter passage under the action of a spring, and means for adjusting said plug valve to regulate the air admitted to said latter passage, substantially as set forth.
3. In a carburetor for an internal combustion engine, the combination of a main passageway, a tubular slideable throttle valve controlling said passageway, a choke tube coaxial with said throttle valve projecting into said passageway and having its axis transverse thereto, a fuel nozzle within said choke tube between which latter and the nozzle is a restricted annular space, a passage adjacent the inlet of said choke for uncontrolled entry into said annular space of a small quantity of primary air, a lateral aperture in the side of said choke tube having its lower edge substantially level with the outlet of the fuel nozzle, a passage connecting said aperture with the atmosphere, a plug valve adapted normally to close the inlet to said latter passage under the action of a spring, and means for adjusting said plug valve to regulate the air admitted to said latter passage, substantially as set forth.
4. In a carburetor for an internal combustion engine, the combination of a body, a horizontal main passageway therein, a tubular throttle valve slideable transversely across said passageway, a choke tube coaxial with said throttle valve, a parallel sided throat in said choke tube, a fuel nozzle having parallel sides arranged in said choke and providing between it and the choke tube a relatively long and restricted passage for the supply of primary air, an opening in said

carburetor body adjacent the inlet of said choke for uncontrolled entry of primary air into said annular space, a lateral aperture in the side of said choke tube having its lower edge substantially level with the outlet of said fuel nozzle, a horizontal passage connecting said aperture with the base of a vertical bore in the carburetor body, an aperture in the side of said bore connecting the interior of said bore with the atmosphere, a plug valve normally closing said aperture in said bore under spring pressure, and means for positively actuating said plug valve to admit air into said vertical bore and thereby to the interior of said choke tube, substantially as set forth.

In testimony whereof I have signed my name to this specification.

WILLIAM LESLIE GUY.
